CENTERLESS GRINDING MACHINE
ATTACHMENTArthur F. Madison, Detroit, Mich., assignor to
Bower Roller Bearing Company, Detroit, Mich.,
a corporation of Michigan

Application May 9, 1946, Serial No. 668,557

20 Claims. (Cl. 51—236)

1

This invention relates to grinding machines, and in particular, to so-called centerless grinding machines for grinding the internal surfaces of annular workpieces such as bushings, sleeves, bearing cones, retaining rings and the like.

One object of this invention is to provide an attachment for centerless grinding machines wherein a plurality of annular workpieces may be internally ground simultaneously with internally tapered surfaces.

Another object is to provide an attachment for centerless grinding machines wherein a plurality of annular workpieces with internally tapered surfaces are supported and rotated in axially offset relationship for simultaneous grinding by a grinding wheel engaging such surfaces.

Another object is to provide an attachment for centerless grinding machines as set forth in the preceding objects wherein the workpieces are supported in axially offset relationship between a flanged regulating roll, a flanged support roll and a flanged pressure roll against a rotatable backing member, adjusting means being provided for positioning the rolls in proper relationship.

Another object is to provide an attachment for a centerless grinding machine as set forth in the object immediately preceding, wherein the support roll and pressure rolls are each made up of two subsidiary rolls to take care of the difference in speed of rotation of the two workpieces being simultaneously ground, means being preferably provided for adjusting one subsidiary roll laterally relatively to the other roll in order to correctly position the two internally tapered workpieces in the correct offset relationship.

Another object is to provide a modified attachment for simultaneously grinding internally tapered workpieces mounted and driven in laterally offset relationship wherein one workpiece is supported against a backing member and the other workpiece is supported against an auxiliary backing member positioned between the two workpieces.

Another object is to provide a further modified attachment for centerless grinding machines for simultaneously grinding internally tapered workpieces mounted and driven in laterally offset relationship wherein one workpiece is supported against a backing member and the other workpiece is supported in laterally offset relationship against the first workpiece whereby one workpiece serves as a backing member for the other workpiece.

Other objects and advantages of the invention will become apparent during the course of the

2

following description of the accompanying drawings, wherein:

Figure 1 is a top plan view of an attachment for a centerless grinding machine according to a preferred embodiment of the invention partly in horizontal section immediately above the support rolls, with the pressure rolls omitted and with certain conventional portions of the machine shown diagrammatically;

10 Figure 2 is a vertical section through the centerless grinding machine attachment, taken along the line 2—2 in Figure 1;

Figure 3 is a vertical section along the line 3—3 in Figure 1, showing the workpieces and their supporting and driving mechanism;

15 Figure 4 is a vertically inclined section along the line 4—4 in Figure 2 showing the adjustments for the regulating roll, support rolls and pressure rolls;

20 Figure 5 is a vertical section along the zigzag line 5—5 in Figure 2;

Figure 6 is a fragmentary top plan view, partly in horizontal section, of a modification employing an auxiliary backing member for the outer workpiece;

25 Figure 7 is an end elevation of the modification shown in Figure 6, with the grinding wheel omitted;

Figure 8 is a fragmentary top plan view, partly 30 in section, of a second modification employing the inner workpiece as a backing member for the outer workpiece; and

Figure 9 is an end elevation of the second modification shown in Figure 8, with the grinding wheel omitted;

35 Referring to the drawings in detail, Figures 1 to 5 inclusive, show a preferred embodiment of an attachment for centerless grinding machines according to the present invention, as applied to

40 a conventional centerless grinding machine of a type well known to those skilled in the grinding art. The centerless grinding machine shown, aside from the attachment and modifications of the present invention, is of the type shown generally in the U. S. patent to Blood et al., No.

45 2,050,482, granted August 11, 1936, for a Grinding machine. Its details form no part of the present invention, other than providing means for mounting and driving the attachments, which

50 are substituted for the conventional devices for holding and driving the workpiece as employed in conventional centerless grinding machines of this type. Such conventional grinding machines grind but one workpiece at a time whereas the present attachment and its modifications enable

them to grind two workpieces at one time, thereby greatly increasing the volume of production obtainable from a given machine over a given period of time while maintaining the same high precision hitherto obtained in grinding single workpieces at one time.

For the purposes of the present invention, Figures 1 and 2 show diagrammatically the supporting and driving mechanism of a conventional centerless grinding machine of the above described type as consisting of a bed 10 having longitudinal guideways 10a, such as dovetail guides, along which a carriage 11 is reciprocable. Pivotedly mounted on the carriage 11 is a work head 12 in the form of a turntable swiveled thereon around a pivot indicated by the dotted line 12a. The carriage 11 is reciprocable by the conventional power-operated means (not shown) so as to advance and withdraw the workpieces from the grinding wheel.

Likewise mounted upon the bed 10 and rising from one end thereof and extending thereacross is a bridge member or grinding head support 13 having transverse guideways 13a in which a grinding head cross slide 14 is reciprocably mounted. The grinding head cross slide is also reciprocated by conventional means such as the screw shaft 14a threadedly engaging a threaded nut 14b on the underside of the cross slide 14 and journaled in a boss 14c extending upwardly from the grinding head support 13. The screw shaft 14a is intermittently rotated by conventional timing means (not shown), the conventional means frequently employed being a cam-controlled mechanism so that the cross slide 14 is fed transversely only while grinding contact is actually maintained with the workpiece.

Journaled on the grinding head cross slide 14 transversely thereof is a grinding wheel shaft 15 which passes through a bore 15a in a housing 15b and is rotated at a high speed by any well-known or conventional means. Mounted on the inner end of the grinding wheel shaft 15 is a grinding wheel 16 of a conventional type.

Reciprocably mounted in a guideway 17 such as a T-slot, in the work head 11 (Figure 1) is a vertical regulating roll support 18 having a pilot rib 19 extending into the guideway 17 and clamped therein by means of a clamping bolt 20 passing through a bore 20a (Figure 2) in the regulating roll support 18 and threadedly engaging a clamping member 21 disposed within the guideway 17.

The regulating roll support 18 is provided with a transverse threaded bore 22 into which is threaded a screw-shaft 23 journaled in the bore 24 of a vertical boss 25 and having a hand wheel 26 mounted on the outer end thereof. When the clamping bolt 20 is loosened, therefore, the turning of the screw shaft 23 by means of the hand wheel 26 moves the regulating roll support 18 to and fro along the guideway or T-slot 17 to the desired position of adjustment, whereupon it is clamped in that position by tightening the clamping bolt 20.

Journaled in the longitudinal bore 27 in the upper end of the grinding wheel support 18 is a tubular shaft 28 carrying a pulley 29 at one end thereof and a regulating wheel or roll, generally designated 30, at the other end. The regulating wheel 30 is keyed at 31 to the hollow shaft 28 and at its periphery is provided with stepped surfaces 32 and 33 of large and smaller diameters separated from one another by an annular abutment shoulder 34.

The hollow shaft 28 (Figures 1 and 2) is provided with a longitudinal bore 35 in which is journaled an ejector shaft 36 operated by any conventional and well-known mechanism. Secured to one end of the ejector shaft 36, as by the pin 37, is the hub 38 of an ejector 39 having a radial arm 40 with an arcuate ejecting member 41 mounted on the outer end thereof and arranged to swing partially around the periphery of the regulating wheel or roll 30 in an upward direction to expel workpieces in a manner subsequently to be described.

Rising from the work-head 12 is a post 42 (Figure 2) carrying on its upper end the base 43 of a vertical support 44, the base 43 being secured to the post 42 by the cap screws or bolts 45 threaded therethrough. The vertical support 44 is provided with a horizontal bore 46 in which is mounted a sleeve 47 secured therein by a set screw 48 threaded through the transverse threaded bore 49 (Figure 1). Journaled in the inner bore 50 of the sleeve 47 is a backing shaft 51 having a retaining collar 52 pinned as at 53 to the rearward end thereof and having a cup-shaped backing member 54 integral with the opposite or forward end thereof.

The backing member 54 is provided with an annular contact face 55 for engagement with the rear face 56 of an annular workpiece 57 having a tapered internal bore 58 to be ground, a front face 59 and a cylindrical peripheral surface 60 adapted to engage and roll upon the peripheral surface 32 of the regulating wheel or roll 30. A similar workpiece 61 similarly provided with an internal tapered bore 62, rear and front faces 63 and 64 and a peripheral surface 65 engages and rolls upon the peripheral surface 33 of the regulating wheel 30 with its rear face 63 in engagement with the annular shoulder 34. The workpieces 57 and 61, for purposes of illustration only, are shown as representing bearing cones or external bearing races for tapered roller bearings for which the present invention provides a greatly enhanced rate of production, when using a given number of centerless grinding machines.

The table 11 is provided with an upstanding portion 66 to which is bolted, as at 67, the base 68 of a vertical support roll bracket 69 having an elongated portion 70 slightly inclined relatively to the horizontal plane. The elongated portion 69 is provided with an undercut grooved guideway consisting of a T-slot 71 in which a slide 72 with a pilot rib 72a is reciprocably mounted. Extending downwardly through a bore 73 in the slide 72 is a clamping bolt 74 threaded into a clamping member 75 (Figure 2) lodged in the guideway 71. The slide 72 is likewise provided with a longitudinal threaded bore 76 into which is threaded a screw shaft 77 having a reduced diameter portion 78 journaled in a bore 79 in an upstanding portion 80 of the elongated portion 70. Secured to the outer end of the reduced diameter portion 78 is a knurled hand wheel 81 for rotating the screw shaft 70 and thereby reciprocating the slide 72 along the grooved guideway 71. The clamping bolt 74 is loosened during such adjustment and tightened after the adjustment has been made.

The forward end of the slide 72 is provided with forwardly extending spaced arms 82 (Figure 1) having aligned grooves 83 and 84 (Figure 4) of partially circular cross-section resembling bores, the sides of which have been cut away. Mounted in the grooves 83 and 84 is a shaft 85 having flattened end portions 86 and 87 with longitudinal

slots 88 adapted to receive clamping bolts 89 threaded into correspondingly threaded holes in the arms 82.

The shaft 85 is provided with an annular shoulder 90 adjacent one end thereof, and this shoulder serves as an abutment for the hub 91 of an eccentric bushing 92 mounted on the shaft 85 and adjustable by being turned relatively thereto. A set screw 93 threaded into a transverse bore 94 in the hub 91 serves to lock the eccentric bushing 92 in its adjusted position relatively to the shaft 85.

Mounted for rotation upon the eccentric bushing 92 (Figure 4) is a workpiece support roll 95 having a peripheral surface 96 which engages the peripheral surface 65 of the outer workpiece 61, the face 63 thereof engaging the abutment shoulder 97 of a peripheral abutment flange 98 on the support roll 95. Mounted directly upon the shaft 85 and rotatable relatively thereto is a smaller support roll 99 having a peripheral surface 100 engaging the peripheral surface 60 of the inner workpiece 57. The support roll 99 abuts the end of the eccentric sleeve 92 (Figure 4) and also the adjacent side wall of the support roll 95, and is provided with a peripheral groove 101 adjacent the latter, so as to space the peripheral surface 100 axially a slight distance therefrom. A collar 102 mounted on the shaft 85 serves to retain the support rolls 95 and 99 in axial adjustment, and for this purpose the collar 102 is provided with a set screw 103 threaded into a transverse threaded bore 104. The outer wall of the support roll 95 abuts a shoulder 105 adjacent the hub 91 of the eccentric bushing 92.

Rising from the slide 72 is a post 106 terminating in a horizontal boss 107 having a bore 108 therethrough. Journalized in the bore 108 is a shaft 109 having an arm 110 secured to the rearward end thereof and having a bracket 111 keyed as at 112 to the forward end thereof (Figure 2). The upper end of the bracket 111 is provided with an elongated portion 113 having an undercut grooved guideway consisting of a T-slot 114. Reciprocably mounted upon the elongated portion 113 of the bracket 111 is an arm 115 having a pilot rib 116 extending downwardly toward the T-slot 114 and having a clamping bolt 117 threaded into a clamping member 118 lodged within the T-slot 114. The arm 115 is provided with a bifurcated outer end 119 upon which are mounted a pair of abutting pressure rolls 120 and 121 which serve as pressure applicators, the manner of mounting being the same as that previously described in connection with the support rolls 95 and 99 and shown in Figure 4, the corresponding parts being similarly designated. Thus, the pressure roll 120 (Figure 5) is provided with an eccentric adjustment relatively to the upper shaft 85 and the pressure roll 121 rotatable thereon just as the support roll 95 is provided with an eccentric adjustment relatively to the lower shaft 85 and to the support roll 99 mounted thereon. The pressure roll 120 is provided with a peripheral abutment flange 122 having an abutment shoulder 123 similar in construction and purpose to the abutment flange 98 on the support roll 95.

In order to urge the workpieces 57 and 61 into firm engagement with the backing member 54 and abutment flanges 98 and 122 respectively, the various axes of rotation are tilted relatively to one another as shown in Fig. 5. In particular, the rearward end of the regulating wheel shaft 28 is tilted upwardly so as to incline the axis of rotation 124 thereof upwardly relatively to the

horizontal axes of rotation 125 and 126 of the backing member 54 and supporting roll 99 respectively. On the other hand, the rearward end of the upper shaft 83 is tilted downwardly so as to tilt the axis of rotation 127 of the pressure roll 120 downwardly and rearwardly. By the eccentric bushing construction previously described, the axes of rotation of the rolls 95 and 120 are parallel to the axes of rotation of the rolls 99 and 121 respectively. As a consequence, when the regulating wheel or roll 30 is rotated, it constantly urges the workpieces 57 and 61 rearwardly against their respective abutments and maintains them in a fixed position axially during the grinding operation.

The arm 110 (Figure 2) is yieldingly urged in an upward direction so as to urge the pressure rolls 120 and 121 downwardly against the workpieces 57 and 61 by the usual conventional means well known in centerless grinding machines of the type to which the present invention is applied, for example by springs (not shown). In such machines, also, conventional means, such as a cam (not shown) is provided for swinging the arm 110 downwardly and thereby lifting the pressure rolls 120 and 121 out of contact with the workpieces 57 and 61 when the grinding operation has been completed, additional means, such as a cam (not shown) being likewise provided to operate in timed relationship therewith and rotate the ejector shaft 36 (Figure 2) clockwise to swing the ejector arm 40 and ejector 41 upwardly to eject the ground workpieces 57 and 61 while the pressure rolls 120 and 121 are swung out of the way. Finally, in such machines, inclined guide troughs or the like are provided above the arm 115 and pressure rolls 120 and 121 to contain and feed the unground workpieces 57 and 61 downwardly to the positions shown in Figure 2 and similar inclined guide troughs are provided above the regulating wheel or roll 30 to carry away the workpieces 57 and 61 after they have been ground and ejected by the ejector 41 as it swings upwardly.

45 *Operation of the form shown in Figures 1 to 5 inclusive*

In setting up the machine with the form of attachment shown in Figures 1 to 5 inclusive, a number of adjustments are made before production grinding is commenced. The abutment face 55 of the backing member 54 is accurately trued so as to rotate evenly. The abutment shoulders 97 and 123 of the support roll 95 and pressure roll 120 respectively are then lined up by loosening the bolts 89 and sliding the shaft 85 axially until the said shoulders lie in the same plane as the abutment shoulder 34 of the regulating wheel or roll 30 at their respective points of contact with the workpieces 57 and 61, these flanges being also adjusted to be parallel to the abutment face 55 of the backing member 54. The support rolls 95 and 99 are then adjusted by moving the slide 72 (Figure 2) by means of the screw shaft 77 and hand wheel 81 until the inner workpiece 57 is exactly centered with respect to the axis of rotation 125 of the backing member 54. In a similar manner, the regulating wheel 30 is adjusted horizontally by means of the screw shaft 23 and hand wheel 26 (Figure 2) until the inner workpiece 57 is so centered. The clamping bolts 74 and 116 are then tightened to clamp the assemblies in their adjusted position.

The set screw 93 (Figure 4) is then loosened and the eccentric bushing 92 turned until the

outer workpiece 61 is placed with its center on the same horizontal level as the center of the inner workpiece 57, that is, at the same center height. The pressure roll 120 is similarly adjusted by means of its eccentric bushing 92.

The work head 12 is now adjusted by swinging it around its vertical pivot 129 until it is presented to the grinding wheel 16 at the proper angle to grind the conical surface 58 of the inner workpiece 57 to the correct taper. The support roll 95 and pressure roll 120 are then adjusted axially until the conical surface 62 of the outer workpiece 61 is likewise ground to the correct taper and size. Finally, the backing member 54 is adjusted axially (Figure 1) until the inner workpiece 57 is ground to the correct size. The machine is now ready for precision grinding.

In operation, the workpieces are mounted in tandem in the parallel inclined troughs (not shown) above the arm 115 and pressure rolls 120 and 121, and the machine is started in operation. By the conventional mechanism previously described, the arm 115 is swung upwardly in timed relationship with the ejector 41 around the axis of the shaft 109 (Figure 2), permitting a pair of workpieces 57 and 61 to drop downwardly into the position shown in Figures 1, 2 and 5. The inner workpiece 57 comes to rest in the position shown in Figure 3 with its periphery 60 resting upon the peripheral surfaces 32 and 100 of the regulating wheel or roll 30 and inner support roll 99 respectively, and with its inner face 56 in abutment with the contact or abutment face 55 of the backing member 54. The inclination of the various axes of rotation (Figure 5), as previously described, causes the inner workpiece 57 to be urged into this position.

The outer workpiece 61, on the other hand, drops into position with its periphery 65 engaging the peripheral surfaces 33 and 96 of the regulating wheel or roll 30 and support roll 95 respectively, with its inner face 63 engaging the annular shoulders 34 and 97 thereof respectively. The same tilting of the various axes of rotation (Figure 5) as previously described, also constantly urges the outer workpiece 61 into this abutting relationship. The carriage 11 is then moved forwardly in timed relationship toward the grinding wheel 16 and reciprocates axially in that position during grinding, thereby simultaneously grinding the internal conical surfaces 58 and 62 of the workpieces 57 and 61 respectively.

When the grinding has been completed, as determined by the timing of reciprocation of the carriage 11, the latter is automatically retracted. The cam mechanism by which the arm 110 is operated then comes into play to rotate the shaft 109 and swing the arm 115 and pressure rolls 120 and 121 upwardly out of the way. Finally, the cam mechanism which swings the ejector shaft 36 in timed relationship with the previously described operation rotates the shaft 36 to swing the arm 40 and ejector 41 upwardly (Figure 2), pushing the workpieces 57 and 61 upwardly to the right into parallel troughs which carry them away to suitable receptacles. Arcuate guides (not shown) are conventionally provided for assisting the ejection of the workpieces 57 and 61 along the arcuate paths substantially concentric with the axis of the regulating wheel 30.

When the ground workpieces 57 and 61 have thus been ejected and cleared, another pair of workpieces drops down into the space vacated by the ground workpieces just ejected, the cam

mechanism causes the arm 110 to be swung upwardly, moving the pressure rolls 120 and 121 downwardly into engagement with the new workpieces, whereupon the foregoing cycle of operations is repeated. Thus, the attachment of the present invention effects the grinding of a pair of workpieces simultaneously with tapered internal surfaces instead of a single workpiece as in prior machines and as in the conventional machine to which the present attachment is applied. The present invention, therefore, substantially doubles the production of each centerless grinding machine and effects a great saving both in the cost of the original equipment and in the cost of each workpiece.

Modification employing auxiliary backing member for outer workpiece (Figures 6 and 7)

The modified attachment shown in Figures 6 and 7 is generally similar to the preferred form of the invention shown in Figures 1 to 5 inclusive, and corresponding parts are similarly designated. The construction of the support rolls 95 and 99 and the pressure rolls 120 and 121 and their supporting and adjusting mechanisms are identical with the construction described in Figures 1 to 5 inclusive, except that the abutment flanges 98 and 122 with their abutment shoulders 97 and 123 are omitted. Instead, the respective rolls 95 and 120 are annularly grooved in the positions previously occupied by their respective flanges 98 and 122 as at 130 and 131.

The vertical support 44 is provided with a laterally extended portion 132 (Figure 6) having a bore 133 in which is mounted an auxiliary backing shaft 134. The latter is held in position by a set screw 135 threaded through a bore 136 in a boss 137 on the laterally extended portion 132.

The forward end of the shaft 134 is provided with a threaded bore 138 into which is threaded a cap screw 139, the shank of which passes through an elongated slot 140 in a bifurcated abutment arm 141, this assembly constituting the auxiliary backing member 142. The bifurcated arm 141 is provided with an arcuately extended end portion 143 having dome-like contact portions 144 at the upper and lower ends thereof. The contact portions 144 are preferably of tool steel, tungsten carbide or other wear-resisting substance, and serve as abutment members engaging the rearward face 63 of the outer workpiece 61. In this way, the modification shown in Figures 6 and 7 differs from the form shown in Figures 1 to 5 inclusive, the abutment shoulders 97 and 123 on the flanges 98 and 122 of the support roll 95 and pressure roll 120 of the principal form of the invention being omitted.

The adjustments of the modification shown in Figures 6 and 7 are generally similar to those previously described in connection with Figures 1 to 5 inclusive, in that the face 55 of the backing member 54 is trued and the support roll 99 and regulating wheel or roll 30 are adjusted to place the inner workpiece 57 concentric with the rotating member 54 as previously described. The two hardened contact portions 144 on the abutment arm 141 are then trued so as to be in the same plane as the abutment shoulder 34 of the regulating wheel 23 and also parallel with the contact space 55 of the backing member 54. The outer rolls 95 and 120 are then adjusted by means of their eccentric bushings 122 (Figure 4) in the manner previously described, to place the outer workpiece 61 at the same center height as the inner workpiece 57. The inner workpiece is ad-

justed to be ground to the correct taper of its internal surface 58 by adjusting the workhead 12 around its vertical pivot 12a so as to present the internal surface 58 at the correct angle to the grinding wheel 15. The outside workpiece is then ground to the correct taper by adjusting the auxiliary backing member 142 by moving the shaft 134 thereof longitudinally in the bore 133 (Figure 6). The correct size thereof is obtained by adjusting the amount the grinding head cross slide 14 is fed transversely to the axis 12a of the grinding wheel 16. To grind the tapered internal surface of the inner workpiece to its correct size, the rotatable backing member 54 is moved longitudinally along its axis 125. The machine is now ready for production grinding.

The operation of the modification shown in Figures 6 and 7 is substantially the same as that of the form shown in Figures 1 to 5 inclusive, and hence requires no repetition. The operation differs only in that the outer workpiece 61 is held against the contact points or portions 144 on the auxiliary backing member 142 instead of against the flanges 98 and 122 on the support roll 95 and pressure roll 120 respectively in Figures 1 to 5 inclusive.

Modification employing inner workpiece as backing member for outer workpiece (Figures 8 and 9)

The modification shown in Figures 8 and 9 is generally similar to the modification shown in Figures 6 and 7, except that the auxiliary work support 142 and its associated parts are omitted. Instead, the rearward surface 63 of the outer workpiece 61 directly engages the outer surface 59 of the inner workpiece 57. For this reason, the shoulder 34 between the peripheral portions 32 and 33 of the regulating wheel or roll 30 is moved rearwardly a slight amount (Figure 8) so as to leave a gap or clearance 145 between the shoulder 34 and the rearward surface 63 of the outer workpiece 61.

The adjustment of the machine is substantially the same as that described in connection with the modification shown in Figures 6 and 7 except that the procedure relating to the auxiliary backing member 142 is omitted, because of the absence of that member. In the modification of Figures 8 and 9, the axial thicknesses of the workpiece 57 must be carefully maintained within close tolerances because the axial thicknesses of the inner workpieces 57 directly determine the position axially which will be occupied by the outer workpieces 61 by reason of the fact that the inner workpieces 57 serve as backing members for the outer workpieces 61.

The operation of the modification shown in Figures 8 and 9 is also substantially the same as that set forth in connection with the principal form of the invention shown in Figures 1 to 5 inclusive, except that the procedure relating to the flanges 98 and 122 on the support roll 95 and pressure roll 120 is omitted because these flanges are lacking.

While I have shown and described my invention in detail, it is to be understood that the same is to be limited only by the appended claims, for many changes may be made without departing from the spirit and scope of my invention.

What I claim is:

1. An attachment for internally grinding a pair of workpieces simultaneously on a centerless grinding machine having supporting structures for a regulating roll, a support roll, a pressure

roll, and a backing member, and a driving structure for one of said rolls, said attachment comprising a rotary regulating device drivingly connected to said driving structure and having a plurality of radially offset workpiece engaging paths thereon, a backing member mounted on one of said supporting structures and abutting one of said workpieces, a plurality of radially offset workpiece supports mounted on another of said supporting structures, and a plurality of radially offset pressure applicators mounted on another of said supporting structures, said workpieces being disposed in radially offset relationship between said regulating device, said workpiece supports and said pressure applicators and in peripheral engagement therewith.

2. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of spaced peripheral workpiece engaging paths thereon, a backing member mounted on one side of said supporting structures and abutting one of said workpieces, a plurality of offset workpiece supports mounted on another of said supporting structures, and a plurality of offset pressure applicators mounted on another of said supporting structures, said workpieces being disposed in offset relationship between said regulating device, said workpiece supports and said pressure applicators and in peripheral engagement therewith.

3. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of workpiece engaging paths thereon of different diameters, a backing member mounted on one of said supporting structures and abutting one of said workpieces, a plurality of offset workpiece supports mounted on another of said supporting structures, and a plurality of offset pressure applicators mounted on another of said supporting structures, said workpieces being disposed in offset relationship between said regulating device, said workpiece supports and said pressure applicators and in peripheral engagement therewith.

4. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of stepped workpiece engaging paths thereon at different distances from the axis of rotation thereof, a backing member mounted on one of said supporting structures and abutting one of said workpieces, a plurality of offset workpiece supports mounted on another of said supporting structures, and a plurality of offset pressure applicators mounted on another of said supporting structures, said workpieces being disposed in offset relationship between said regulating device,

13

supports mounted on another of said supporting structures on spaced axes of rotation, an eccentric member disposed between one of said workpiece supports and its supporting structure and adjustably rotatable relatively thereto, and a plurality of offset pressure applicators mounted on another of said supporting structures, said workpieces being disposed in offset relationship between said regulating device, said workpiece supports and said pressure applicators and in peripheral engagement therewith.

12. An attachment for internally grinding a pair of workpieces simultaneously on a centerless grinding machine having supporting structures for a regulating roll, a support roll, a pressure roll, and a backing member, and a driving structure for one of said rolls said attachment comprising a rotary regulating device drivingly connected to said driving structure and having a plurality of workpiece engaging paths thereon, a backing member mounted on one of said supporting structures and abutting one of said workpieces, a plurality of offset workpiece supports mounted on another of said supporting structures, a plurality of offset rotatable pressure applicators mounted on another of said supporting structures, and an eccentric member disposed between one of said pressure applicators and its supporting structure and adjustably rotatable relatively thereto, said workpieces being disposed in offset relationship between said regulating device, said workpiece supports and said pressure applicators and in peripheral engagement therewith.

13. An attachment for internally grinding a pair of workpieces simultaneously on a centerless grinding machine having supporting structures for a regulating roll, a support roll, a pressure roll, and a backing member, and a driving structure for one of said rolls said attachment comprising a rotary regulating device drivingly connected to said driving structure and having a plurality of workpiece engaging paths thereon, a backing member mounted on one of said supporting structures and abutting one of said workpieces, a plurality of offset rotatable workpiece supports mounted on another of said supporting structures on spaced axes of rotation, an eccentric member disposed between one of said workpiece supports and its supporting structure and adjustably rotatable relatively thereto, a plurality of offset rotatable pressure applicators mounted on another of said supporting structures, and an eccentric member disposed between one of said pressure applicators and its supporting structure and adjustably rotatable relatively thereto, said workpieces being disposed in offset relationship between said regulating device, said workpiece supports and said pressure applicators and in peripheral engagement therewith.

14. An attachment for internally grinding a pair of workpieces simultaneously on a centerless grinding machine having supporting structures for a regulating roll, a support roll, a pressure roll, and a backing member, and a driving structure for one of said rolls said attachment comprising a rotary regulating device drivingly connected to said driving structure and having a plurality of workpiece engaging paths thereon, a backing member mounted on one of said supporting structures and abutting one of said workpieces, a plurality of offset workpiece supports mounted on another of said supporting struc-

14

tures, a plurality of offset pressure applicators mounted on another of said supporting structures, and an auxiliary backing member mounted on one of said structures and having an abutment portion extending between said workpieces and engaging one of said workpieces, said workpieces being disposed in offset relationship between said regulating device, said workpiece supports and said pressure applicators and in peripheral engagement therewith.

15. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of workpiece engaging paths thereon, a backing member mounted on one of said supporting structures and abutting one of said workpieces, a plurality of offset workpiece supports mounted on another of said supporting structures, a plurality of offset pressure applicators mounted on another of said supporting structures, and an auxiliary backing member mounted on one of said structures and having an abutment portion with spaced contact portions extending between said workpieces and engaging one of said workpieces, said workpieces being disposed in offset relationship between said regulating device, said workpiece supports and said pressure applicators and in peripheral engagement therewith.

16. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of workpiece engaging paths thereon, a backing member mounted on one of said supporting structures and abutting one of said workpieces, a plurality of offset workpiece supports mounted on another of said supporting structures, a plurality of offset pressure applicators mounted on another of said supporting structures, and an auxiliary backing member mounted on one of said structures and having an abutment portion extending between said workpieces and engaging one of said workpieces, said auxiliary backing member being adjustably movable axially relatively to the workpiece engaged thereby, said workpieces being disposed in offset relationship between said regulating device, said workpiece supports and said pressure applicators and in peripheral engagement therewith.

17. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of workpiece engaging paths thereon, a backing member mounted on one of said supporting structures and abutting one of said workpieces, a plurality of offset rotatable workpiece supports mounted on another of said supporting structures on spaced axes of rotation, a plurality of offset pressure applicators mounted on another of said supporting structures, and an auxiliary backing member mounted on one of said struc-

tures and having an abutment portion extending between said workpieces and engaging one of said workpieces, said workpieces being disposed in offset relationship between said regulating device, said workpiece supports and said pressure applicators and in peripheral engagement therewith.

18. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of workpiece engaging paths thereon, a backing member mounted on one of said supporting structures and abutting one of said workpieces, a plurality of offset workpiece supports mounted on another of said supporting structures, a plurality of offset rotatable pressure applicators mounted on another of said supporting structures on spaced axes of rotation, and an auxiliary backing member mounted on one of said structures and having an abutment portion extending between said workpieces and engaging one of said workpieces, said workpieces being disposed in offset relationship between said regulating device, said workpiece supports and said pressure applicators and in peripheral engagement therewith.

19. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of workpiece engaging paths thereon, a backing member mounted on one of said supporting structures and abutting one of said workpieces, a plurality of offset rotatable workpiece supports mounted on another of said supporting

structures on spaced axes of rotation, a plurality of offset rotatable pressure applicators mounted on another of said supporting structures on spaced axes of rotation, and an auxiliary backing member mounted on one of said structures and having an abutment portion extending between said workpieces and engaging one of said workpieces, said workpieces being disposed in offset relationship between said regulating device, said workpiece supports and said pressure applicators and in peripheral engagement therewith.

20. An attachment for internally grinding a pair of workpieces simultaneously on a centerless grinding machine having supporting structures for a regulating roll, a support roll, a pressure roll, and a backing member, and a driving structure for one of said rolls, said attachment comprising a rotary regulating device drivingly connected to said driving structure and having a plurality of radially offset workpiece engaging paths thereon, a backing member mounted on one of said supporting structures, and a plurality of radially offset pressure applicators mounted on another of said supporting structures, said workpieces being disposed in radially offset relationship between said regulating device, said workpiece supports and said pressure applicators and in peripheral engagement therewith, one of said workpieces being disposed in direct abutting relationship with the other workpiece adjacent thereto.

ARTHUR F. MADISON.
